UNITED STATES PATENT OFFICE.

EDWARD ROCHE, OF PROVIDENCE, RHODE ISLAND.

BOOT OR SHOE. **REISSUED**

SPECIFICATION forming part of Letters Patent No. 634,588, dated October 10, 1899.

Application filed November 4, 1895. Serial No. 567,831. (No model.)

To all whom it may concern:

Be it known that I, EDWARD ROCHE, of Providence, in the county of Providence and State of Rhode Island, have invented certain new and useful Improvements in Boots or Shoes, of which the following is a specification.

This invention relates to boots and shoes, and has for its object to provide such a construction as will prevent and cure what is termed "flat-footedness."

A further object of my invention is to provide such means in the construction of boots and shoes as will relieve the wearer of the shock experienced by the heel striking the ground or sidewalk, as also to provide a boot or shoe which will enable the wearer to walk with greater ease and less fatigue than with the shoes as now commonly constructed.

It is also the object of my invention to provide a support for the tarsal bones for the prevention and cure of flat-footedness, gout, and rheumatic pains, the shoes as commonly constructed failing to support the tarsal bones, allowing them to drop and the muscles to relax, causing excruciating pains in the metatarsal bones, the pain extending to the upper portion of the latter.

Referring now to the drawings, forming a portion of this specification, in which like letters of reference indicate similar parts in the several views, Figure 1 is a vertical section of a human foot having a shoe thereon constructed in accordance with my invention and showing the elements thereof in their proper positions. Fig. 2 is a perspective view of the spring employed by me. Fig. 3 is a perspective view of the bearing-plate for the spring.

Referring now to the drawings in operating in accordance with my invention, I arrange within a shoe *c* an inner sole *e*, which is left loose from the back of the heel to the metatarsal bones, and I arrange upon this inner sole and in such a position as to receive the ball of the foot a plate *g*, held immovably in place and curved to conform with the shape of the insole, as shown. The said plate extends rearwardly a sufficient distance to receive the movable upwardly-curved end *f'* of the spring-plate *f*, which latter is curved to conform to the arch of the foot and extends

rearwardly throughout the length of the shoe, the rear end of this plate lying against the rear wall of the shoe, in which position it is held in place by means of a tack passing into the insole *e* or in any other desired manner. The curve of the spring *f* is such that under pressure of the foot in the operation of walking its free end *f'* will have a movement on the face of the plate *g* and the spring action of the plate will extend beneath a portion of the heel of the foot. By this construction, as will be readily seen, the plate *f* not only supports the arch of the foot and prevents dropping of the bones, but forms a yieldable support for a portion of the heel, thus absorbing a large portion of the shock incident to walking.

As will be appreciated, the usual heavy sole *a* and the heel *b* are comprised by the shoe, and a second or false insole *d* is arranged upon the plates *g* and *f* to offer a smooth surface and a soft bearing for the foot.

Shoes made in accordance with my invention are preferably constructed as "turned" shoes, and when so constructed the sole is attached to the upper in the manner common to this class.

Having thus described my invention, what I claim is—

1. A boot or shoe provided with a false inner sole extending from the ball of the foot to the heel, an inner sole extending the length of the foot or shoe and having its heel and waist portion loose and a curved spring interposed between the false inner sole and the loose portion of the inner sole.

2. A boot or shoe provided with an inner sole and a false inner sole, a bearing-plate secured to the inner sole to receive pressure of the ball of the foot, and a curved spring secured to the heel between said soles and having its forward end resting loosely upon said bearing-plate.

In testimony whereof I have signed my name to this specification, in the presence of two subscribing witnesses, this 21st day of September, A. D. 1895.

EDWARD ROCHE.

Witnesses:

JOHN DORAN,
FRANK W. JOHNSON.
